COMPENSATOR FOR NAIL DRIVING
MECHANISMS

Herbert E. Twomley, Riverside, Calif., assignor,
by mesne assignments, to Food Machinery
Corporation, a corporation of Delaware

Application October 27, 1934, Serial No. 750,289

5 Claims. (Cl. 1-10)

My invention relates to nailing machines, and has particular reference to a device for automatically adjusting the length of movement of nail-driving mechanisms, or automatically compensating for varying distances through which the 5 nails are to be driven.

In nailing machines for nailing box parts together it frequently occurs that some of the box parts vary considerably in size and thickness so 10 that a machine which is set to nail a given size of box with given sizes of parts will not drive nails accurately if there is a slight variation in the thickness of the parts to be nailed together. This is particularly apparent in the manufacture 15 of boxes where the nailing machines are employed to nail side, bottom and top boards upon cut ends wherein the thickness of the shooks or side, bottom and top boards varies considerably, so that a machine which is correctly adjusted to 20 drive nails flush with the surface of the shooks, or side boards, will, when a shook of different thickness is encountered, drive the nails either below the surface of the board or not quite flush with the surface of the shook or board. This is 25 undesirable primarily because it places an undue and unnecessary strain upon the operating parts of the machine, and, secondarily, because it does not produce a strong, substantial box as would be produced were the nails always driven to a position 30 just flush with the top surface of the board or shook.

In the making of certain types of boxes, such as those employed for the packing and transportation of fruits, it is the common practice to make 35 certain of the boxes which are to be used for domestic shipment with the side, bottom and top boards of a predetermined thickness, while, if the boxes are to be used in export service, the sides, bottoms and tops of the boxes are formed of 40 either shooks or boards which are of twice the domestic thickness or the sides, bottoms and tops of the boxes are constructed by applying two of the boards, one superimposed upon the other so that the nails which are to be driven into these 45 export boxes must be driven flush with a board equaling twice the thickness of the domestic box.

It is, therefore, an object of my invention to 50 provide a nailing mechanism which, when adjusted for any predetermined size of box, or any predetermined thickness of shook or boards which 55 are to be used thereon, can also be used to drive the nails in boxes which vary slightly in dimensions or in which the boards or shooks employed vary considerably in thickness.

Another object of the invention is to provide

a nailing mechanism of the character set forth in the preceding paragraph wherein it is impossible to apply greater than a predetermined force to the nail, and it is impossible to press or drive the nail to a position further than flush 5 with the top surface of the board or shook through which the nail is to be driven.

Another object of the invention is to provide a nailing mechanism of the character set forth, in which the nail-driving punches employed are 10 connected to a nail driving head which is permitted to travel the same distance irrespective of the thickness of the box or shook which is being operated upon and in which the nail punch will only move through a distance necessary to drive 15 the nail flush with the top surface of the board or shook.

Another object of the invention is to provide a nail-driving mechanism of the character set 20 forth, in which the nail punches are connected to the nail-driving head by mechanism which will apply only a predetermined pressure to the nail.

Another object of the invention is to provide a nail-driving mechanism in which the nail 25 punches employed are connected to the nail-driving head and to nail chucks so that the nail punches can only be driven to a point flush with the lower surface of the nail chucks and in which the nail punches are positively stopped in such 30 position irrespective of the movement of the nail-driving head.

Another object of the invention is to provide a nail-driving mechanism in which the nail 35 punches are permanently connected to the nail-driving head by link mechanism which provides for the transmission of a predetermined force from the driving head to the nail punch but in which, when such force is exceeded, will so change the direction in which the force is transmitted 40 between the driving head and the punch that the effective force transmitted to the nail punch will be reduced substantially to nothing.

Other objects and advantages will be apparent 45 from a study of the following specifications, read in connection with the accompanying drawings, wherein

Figure 1 is a side elevational view shown partly in section of a nail-driving mechanism constructed in accordance with my invention; 50

Figure 2 is a front elevational view, partly in section of the mechanism illustrated in Figure 1;

Figure 3 is a side elevational view partly in section illustrating the operation of my nail- 55

driving mechanism when the box or shook is of a predetermined thickness corresponding to the initial setting of the nail-driving mechanism;

5 Figure 4 is a view similar to Figure 3, illustrating the operation of my nail-driving mechanism when the shook is of slightly greater thickness than that shown in Figure 3;

10 Figure 5 is a view similar to Figure 3, illustrating the operation of my nail-driving mechanism when the shook or board operated upon is of considerably greater thickness than that shown in Figure 3.

15 Referring to the drawings, I have illustrated only a portion of the nail-driving machine, it being understood that the nail-driving mechanism illustrated herein may be readily adapted to any well-known type of nail-driving mechanism or box-making mechanism, such as are shown in United States Letters Patent No. 1,576,213, granted to George David Parker on March 9, 20 1926, for Combined cover press and nailing machine.

25 The nailing machine, or a portion of which is illustrated herein, comprises the usual frame, not shown, from which rises uprights 1 constituting vertically extending guide rails upon which a nail-driving head 2 is reciprocably mounted. The rails 1, on opposite sides of the machine, may be connected by any suitable cross bars or braces, illustrated herein as a pair of rods 3 and 4 which are connected to a clamp 5 mounted directly upon the upper end of the rail 1. The cross head 2 is illustrated as comprising a bearing member 6 slidably mounted upon the upright 30 or rail 1, it being understood that upon the opposite side of the machine a similar bearing 6 is mounted upon the rail at that side of the machine. The bearings 6 on opposite sides of the machine are interconnected by means of cross 35 bars or rods 7 and 8 which in turn constitute hangers upon which the nail-driving mechanisms may be supported.

40 The nail-driving mechanisms may comprise a nail chuck assembly 10, illustrated herein as 45 comprising an elongated guide 11 upon the lower end of which is mounted a nail chuck body 12 having a pair of jaws 13 normally held in close 50 relation with each other by means of a pair of springs 14 and 15 mounted upon opposite sides 55 of the guide 11. The nail chuck jaws 13 may be constructed in any well-known manner, as that illustrated herein as a pair of blocks, the meeting faces of which are provided with suitable complementary grooves 16 adapted to receive and hold a nail 17 in a vertical position aligned with the vertical axis of the guide 11.

60 As will be understood by those skilled in the art, the lower face of the chuck body 12 constitutes the nailing line or lower limit to which 65 the nail 17 should be driven, such nail chuck body 12 being usually brought into contact with the upper surface of the board to be nailed so that the nail, when driven completely through the nail chucks, will be just flush with the upper 70 surface of the board so nailed.

75 The nails are driven by a nail driver 19 reciprocably mounted in the guide 11. The nail driver 19 is preferably formed as a rod having an upper portion of enlarged diameter reciprocably mounted in an enlarged vertical bore 20 in the guide 11, while the nail engaging portion of the nail driver 19 is preferably formed with a reduced diameter operating in a vertical bore 18 extending below the bore 20 and of appropriately lesser diameter.

The guide 11 is also provided with a nail channel which may be of any suitable construction to guide a nail into the nail chucks in the position shown in Figures 1 and 2, the form of the nail channel illustrated herein comprising a block 22 having a bore 23 extending therethrough such that when the block 22 is assembled upon the guide 11 and held in place thereon by means of a spring 24 nails dropped into the upper end of the bore 23 will slide downwardly through the 10 guide into the position shown in Figures 1 and 2.

The upper end 20 of the nail driver 19 is illustrated as being connected to a cross head 25 by means of a suitable nut 26. The cross head 25 is illustrated as having a pair of pins 27 and 28 extending laterally therethrough, one on each side of the nail driver 19 and spaced a considerable distance from the longitudinal axis of the nail driver 19. The pin 27 constitutes a bearing upon which is mounted a pair of links 29 and 31, 20 while the pin 28 mounts a pair of similar links 31 and 31'. The links 29 and 30 on the right-hand side, as viewed in Figure 1, the link 29 being illustrated in Fig. 1 as partially broken away so as to permit a view of the link 31 behind the 25 same, are interconnected by means of a pin 32 which extends parallel to the pin 27 but is offset slightly from a vertical plane drawn through the pin 27, the pin 32 being connected directly with the cross bar 7 by means of a secondary link 33, one end of which is mounted upon the cross bar 7 to freely rotate thereon, while the other end of the link 33 is free to rotate upon the pin 32.

Upon the opposite, or left-hand, side of the device, as shown in Figure 1, the links 30 and 31' are similarly interconnected by means of a pin 34 which extends parallel to the pin 28, but is offset slightly from the vertical plane of the pin 28. The pin 34 constitutes a bearing upon which the lower end of a secondary link 35 is rotatably mounted, the upper end of the link 35 being rotatably mounted upon the cross bar 8.

The links 29 and 30 upon the front side of the nail-driving mechanism, as viewed in Figure 1, together with the secondary links 33 and 35, constitute two sets of toggle links connecting the cross head 25 with the cross bars 7 and 8, while the corresponding links 31 and 31' upon the rear side of the nail-driving mechanism, as viewed in Figure 1, together with the links 33 and 35, constitute a similar pair of toggle links interconnecting the cross head 25 with the cross bars 7 and 8.

With the construction thus far described, it will be apparent that when the nail-driving head 2 is drawn downwardly by connecting rods 36 connected to the bearings 6 in the usual manner employed for operating nail-driving heads of nailing machines, the cross bars 7 and 8 will be drawn downwardly and will carry with them the nail drivers 19.

As will be understood by those skilled in the art of nail-driving machines, the usual practice for operating the nail-driving head 2 is to connect the connecting rods 36 to rotatable crank pins so that upon each revolution of the crank pins the nail-driving head 2 will be drawn down through a predetermined distance and then returned to its original position, such as that illustrated in Figures 1 and 2. It follows, therefore, that the nail-driving head 2 will, upon each revolution of the crank pins, be drawn downwardly through the same distance, and that the nail drivers 19 will be moved downwardly through 75

the same distance upon each operation of the nail-driving head 2. When the device is to be used to nail a shook 38 to a box end 37 the machine may be originally adjusted so that when the chuck body 12 is brought into contact with the upper surface of the shook 38, the nail driven by a complete downward movement of the nail-driving head 2 will be just flush with the upper surface of the shook 38. Thus if the shook 38 is used and is of a predetermined thickness for which the machine is initially adjusted, the complete downward movement of the nail-driving head will just drive the nail flush with the upper surface of the shook.

By referring, particularly, to Figures 1, 2, and 3, it will be noted that the shoulder 39, formed by the junction of the enlarged portion 20 of the nail driver 19 with its reduced portion, may be employed as a limit stop, limiting the movement of the nail driver 19 relative to the nail chuck assembly 10 by forming a similar shoulder 40 upon the interior of the guide 11 against which the shoulder 39 abuts when the nail punch has moved a predetermined distance through the nail chuck assembly. As illustrated herein, this limit of movement is just such as will bring the lower end of the nail driver exactly flush with the lower surface of the chuck body 12 so that if the chuck body rests upon the upper surface of the shook 38 the nail driver 19 will move to a position just flush with the upper surface of the shook 38. Thus the lower surface of the chuck body 12 constitutes the "nailing line" to which level the nails will be driven at all times. If the nail chuck body is stopped prior to reaching the lowermost level, as shown in Figure 4, it follows that the nail driver 19 will also be stopped at the new level at which the chuck body 12 has come to rest, because the shoulders 39 and 40 have come together.

As will be understood by those skilled in the art of nailing machines, the nail chuck assembly 10 may be supported directly upon the nail driver 19 so that it lifts and lowers slightly with the movements of the nail driver 19, as by a set screw 50 extending through the guide 11 into a keyway 51 formed in the enlarged upper portion 20 of the nail driver 19, which will lift the nail chuck assembly 10 slightly above the level of the box parts 37 and 38 when the nail-driving head is lifted to its normal position as shown in Figures 1 and 2. The purpose of providing a slight vertical movement for the nail chuck assembly is to permit a greater amount of freedom for the operator of the machine to place the box parts 37 and 38 in the machine prior to the actual nailing operations; while, when the box parts are in position, the nail chuck is permitted to move down slightly to engage the upper surface of the shook 38.

If, however, the box parts are not exactly of the dimensions illustrated in Figure 3, but are slightly larger as shown in Figure 4, in which the shook 38a is illustrated as being of slightly greater thickness than the shook 38, it will be apparent that while the nail-driving head 2 is moved downwardly to the same distance, the nail chuck assembly 10 and the nail driver 19 will not be capable of moving to the same lower position as shown in Figure 3, but will be stopped at a higher point, depending upon the thickness of the shook 38a.

By referring to Figure 4, it will be apparent that the nail driver 19 has moved down through the nail chuck assembly 10 to position its shoul-

der 39 directly upon the shoulder 40 formed upon the guide 11, thus bring the extreme lower end of the nail driver 19 flush with the lower surface of the chuck body 12, but the chuck body 12 is now resting upon the upper surface of the shook 38a at a higher level than that illustrated in Figure 3. Thus downward movement of the nail driver 19 has been arrested prior to the arrival of the nail-driving head 2 to its lowermost position.

From an inspection of Fig. 1, it will be observed that while the rod 3 and the pin 34 are in substantial vertical alignment so that downward movement of the driving head 2 will transmit a direct vertical force to the links 30, the pin 28 which connects the link 30 with the cross head 25 on the nail punch is offset out of vertical alignment with the pin 34. Thus the downward movement of the driving head 2 will transmit a force to the nail driver 19 of which the vertical component will be substantially large. The same arrangement of offset of the pin 27 relative to the vertical alignment of the pin 32 and the rod 37 is employed for the opposite toggle links 29 and 33 and the two sets of links 30-35 and 29-33 may be interconnected by means of a relatively light spring 43 tending to hold these links from outward movement. Thus the force exerted by the nail-driving head 2 upon the nail driver 19 during the movement of the driver 19 down through the guide 11, will be substantially the same as though there was a direct connection of the nail driver 19 with the cross head 2 until the shoulders 39 and 40 come in contact with each other. This force, therefore, will be sufficient to drive the nail through the chuck assembly and into the board or chuck. However, when the shoulders 39 and 40 engage each other, further downward movement of the nail-driving head 2 will cause the toggle links 30-35 and 29-33 to "break", thus relieving further pressure upon the nail driver 19.

It will be apparent from an inspection of Figure 1 that the spring 43 is connected to the links 29 and 30 upon outwardly extending arms 43' which extend to a considerable distance laterally of the pins 32 and 34, respectively. Thus a slight "breaking" of the toggles 30-35 and 29-33 will swing the outer ends of the arms 43' toward horizontal alignment with the pins 27 and 28, the effect of which is to reduce the vertical component of the force transmitted by the toggle links from the nail-driving head 2 to the nail driver 19 to greatly reduced value, approaching zero, as the ends of the arms 43' approach horizontal alignment with the pins 27 and 28. The effect of the outward movement or breaking of the toggle links 30-35 and 29-33 will, therefore, be to substantially cancel any downward pressure upon the nail driver 19 after the shoulders 39 and 40 have been brought into engagement with each other. The toggle links 31 and 31' at the rear, as viewed in Figure 1, are similarly interconnected by a spring 42 connecting two arms identical with the arms 43' and operating in the same manner so that by properly selecting the strength of the springs 42 and 43, and by properly selecting the length of the extending arms 43', the desired force to be exerted upon the nail by the initial movement of the driving head 42 may be adjusted. Also, it will be observed that the links 29 and 30 have inwardly extending arms 47 formed thereon, the meeting surfaces of which constitute stops limiting the inward movement or "straightening" 75

of the toggle links 30-35 and 29-33, and by properly selecting the lengths of the arms 47 the initial vertical component of the force transmitted from the nail-driving head to the nail punch 20 may be adjusted.

For convenience, the springs 42 and 43 may have one of their ends connected to a single cross pin 44 which connects the arms 33' of the links 29 and 31, while a similar pin 45 may be employed to interconnect the links 30 and 31' to which the opposite ends of the springs 42 and 43 may be secured, the springs being secured to the pins 44 and 45, preferably through a clevis 46 which will permit rotary movement of the pins 15 relative to the springs without producing a bending torsion in the springs. It will be apparent, therefore, that independent of the thickness of the shooks 38 and nail drivers they may be positioned below the upper surface of the particular 20 shook through which the nail is to be driven and no excessive force will be exerted either upon the nail driver or the shook assembly tending to crush the shook or tending to drive the nail 17 below the surface of the shooks 38 or 38a. Thus 25 the toggle joints provided by the links 29-33, 31-33 and 30-35 and 31'-35 constitute a connecting device between the nail driver 19 and the nail-driving head 2 which will transmit a force necessary to drive the nail flush with the shook 30 and then diminish the force, and then, even though further movement of the nail-driving head may occur, the force exerted by such further movement upon the nail driver will be so diminished as to cause substantially no further pressure 35 to be exerted upon the nail punch. Thus while ample force may be transmitted to perform the nail-driving operations, no force is transmitted tending to "over-drive" the nail.

By referring particularly to Figure 5, it will be apparent that even though the shook 38b shown therein is of considerably greater thickness than the shook 38a shown in Figure 4, the same results of driving the nail flush with the upper surface 40 of the particular shook under consideration will occur, the toggle connections moving outwardly to a greater or less distance depending upon the thickness of the shooks 38, 38a or 38b through which the nail is to be driven.

While I have shown and described the preferred embodiment of my invention herein, I do not wish to be limited to any of the details of construction shown herein, except as defined in the appended claims.

I claim:

1. In a mechanism for driving nails through boards, a nail-driving head movable through a predetermined distance toward said board, a nail driver, means connecting said nail driver with said nail-driving head for movement therewith, 5 said connecting means including means for limiting the force exerted by said nail-driving head upon said nail driver to a predetermined value.

2. In a nail-driving mechanism, a nail-driving head movable through a predetermined distance 10 upon each operation thereof, a nail driver, means connecting said nail driver with said nail-driving head to transmit the force of the movement of said nail-driving head directly to said nail driver, yielding means on said connecting means 15 operatively responsive to the exertion of a predetermined resistance to movement of said nail driver for diminishing the force transmitted from said nail-driving head to said nail driver.

3. In a nail-driving mechanism, a nail-driving 20 head movable through a predetermined distance upon each of its operations, a nail driver, link means connecting said nail-driving head and said nail driver, movable through one position, transmitting the force of movement of said nail-driving 25 head in a direct line to said nail driver to another position transmitting said force to said nail driver indirectly, and means on said link means operably responsive to the exertion of a predetermined resistance to the movement of 30 said nail driver for yieldingly holding said link means in said first position until said predetermined resistance is exerted.

4. In a nail-driving mechanism, a nail-driving head movable through a predetermined distance 35 upon each of its operations, a nail driver, a toggle link connecting said nail driver with said nail-driving head and operably responsive to the resistance opposing said nail driver for moving said toggle link from a position transmitting force 40 from said nail-driving head directly to said nail driver to a second position transmitting said force indirectly to said nail driver.

5. In a nail-driving mechanism, a nail-driving head movable through a predetermined distance 45 upon each of its operations, a nail-driver, toggle link means connecting said nail-driver with said nail-driving head, the midpoint of said toggle link means being disaligned with the ends of said toggle link means whereby resistance to movement 50 of said nail-driver will cause said toggle link means to yield, and means opposing the yielding movement of said toggle link means.

HERBERT E. TWOMLEY.
